INSULATED JUG

Herbert M. Piker, Wyoming, Ohio, assignor to The Hamilton-Skotch Corporation, Hamilton, Ohio, a corporation of Ohio

Filed May 18, 1964, Ser. No. 80,036

Term of patent 14 years

(Cl. D58—17)

FIG. 1 is an elevational view of an insulated jug showing my new design;

FIG. 2 is an elevational view thereof taken from the right of FIG. 1;

FIG. 3 is a top plan view thereof; and

FIG. 4 is a bottom plan view thereof.

I claim:

The ornamental design for an insulated jug, substantially as shown.
